US0D1044350S

(12) United States Design Patent (10) Patent No.: US D1,044,350 S
(45) Date of Patent: * Oct. 1, 2024

(54) CABINET

(71) Applicant: Jingning Meige Technology Service Co., Ltd., Zhejiang (CN)

(72) Inventor: Yifan Zhai, Hubei (CN)

(73) Assignee: Jingning Meige Technology Service Co., Ltd., Zhejiang (CN)

() Term: 15 Years

(21) Appl. No.: 29/947,082

(22) Filed: Jun. 13, 2024

(51) LOC (14) Cl. 06-04

(52) U.S. Cl.

USPC D6/671

(57) CLAIM

The ornamental design for a cabinet, as shown and described.

DESCRIPTION

FIG. 1 is a front, right and top perspective view of a cabinet, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 1; and, FIG. 12 is another front, right and top perspective view of the cabinet shown in a position when the cabinet door is open.

The dashed broken lines depict portions of the cabinet that form no part of the claimed design. The dot-dash broken lines in FIGS. 1, 9, 10, and 11 depict the boundaries of the enlargements and form no part of the claimed design.

1 Claim, 12 Drawing Sheets
